[57] ABSTRACT

A sample of molten metal is taken by swinging an elongate arm over the molten metal from a safe distance and by lowering a carried sampling tube into the molten metal to extract a sample. The sample-containing tube is raised and swung to a collecting station, where it is released. The sampling arm is pivotally mounted to swing on a vertical axis and has a receiving clamp at its free end for holding an evacuated sampling tube. Means are also provided for lowering the sampling tube into and lifting it from the molten metal. Individual empty sampling tubes are successively inserted into the receiving clamp by injecting mechanism located at a work station a safe distance from the molten metal but within the lateral swing path of the free end of the arm. The tubes are individually supplied to the injecting mechanism, preferably from storage, by dispensing mechanism. The apparatus can be programmed to execute its sampling cycles automatically at desired frequency, and is preferably mounted upon a movable platform for convenient placement with respect to molten metal to be sampled.

FIG. 9

APPARATUS FOR TAKING SAMPLES OF MOLTEN METAL

BACKGROUND OF THE INVENTION

1. Field

This invention relates to apparatus for sampling molten metals.

2. State of the Art

In order to control the quality of metal castings, it is desirable to take a sample of the metal of each casting for analysis. The ideal time to take a sample is while the metal is still in the molten state, since corrections can be made immediately for subsequent pours. However, due to the high temperature possibility of splashing, manual taking of molten samples is extremely hazardous. It is therefore customary to wait until the cast metal has solidified and to then take a "plug" for analysis, even though this procedure is uneconomical and results in considerable delay.

OBJECTIVES

A primary objective in the making of this invention was to provide for the taking of samples of metal while still molten but without danger of injury to workmen, and preferably to do this automatically at predetermined time intervals so as to effect savings in manpower and enable the obtaining of uniform samples.

SUMMARY OF THE INVENTION

The apparatus of the invention includes a sampling arm extending laterally from pivotal attachment to a support, so that it can be swung at least laterally relative to the support. The arm is equipped at its free end with means for receiving and holding replaceable sampling tubes, preferably evacuated glass tubes. Means are provided for dipping the held sampling tube into the molten metal to be sampled and for withdrawing the tube therefrom. Additional means are provided for releasing a held tube following the taking of a sample, as are means for replacing empty sampling tubes in the holding means. A motor or other driving mechanism is used to swing the sampling arm around the support, and limit switches or the like are provided to control the length of the pivot arc.

The means for replacing empty sampling tubes is preferably disposed below the tube-holding means at a work station located a safe distance from the molten metal to be sampled but within the swing path of such tube-holding means. The tube-holding means comprises an injector mechanism for preferably feeding individual sampling tubes vertically into the tube-holding means, a container for a plurality of empty sampling tubes, and mechanism for continuously feeding individual tubes from the container into the injector mechanism. For ease of transportation and precise positioning of the apparatus with respect to the molten metal, it is advantageous to mount the sampling arm and the tube-inserting means on a movable platform or frame.

In practice, the apparatus is positioned near the sampling location, so that the support and tube-inserting means are located a safe distance from the molten metal. The arm is then swung around the support to place the tube-holding means and sampling tube at a predetermined position over the molten metal to be sampled, and a sample is taken by lowering the tube into the molten metal, lifting the filled tube, swinging the arm to a sample-collecting station, and releasing the tube with its contained sample. Thus, sensitive control components of the equipment are not subjected to the high temperature and metal splash which are present in the area immediately surrounding the molten metal being sampled.

DESCRIPTION OF THE DRAWINGS

An embodiment of apparatus constituting the best mode presently contemplated of carrying out the invention is shown in the accompanying drawings, in which:

FIG. 1 is a fragmentary top plan view showing the apparatus positioned near a casting wheel for molten metal, with the sampling arm extending over a pour to be sampled, but indicated by dotted lines in its starting and return positions;

FIG. 2, a side elevation looking from the line 2-2 of FIG. 1, and showing the apparatus per se;

FIG. 3, a transverse section through the apparatus taken along the line 3-3 of FIG. 1, showing the sampling arm in elevation;

FIG. 4, a horizontal section taken along line 4-4 of FIG. 3;

FIG. 5, the portion of FIG. 3 enclosed by the line 5 drawn to a considerably larger scale to show details of tube-clamping mechanism;

FIG. 6, a top plan view of the mechanism comprehended by the line 6-6 of FIG. 2;

FIG. 7, a longitudinal vertical section taken along the line 7-7 of FIG. 6;

FIG. 8, a transverse vertical section taken along the line 8-8 of FIG. 1, and

FIG. 9, a schematic wiring diagram of an automated embodiment of the apparatus.

DETAILED DESCRIPTION OF THE ILLUSTRATED EMBODIMENT

As illustrated, the several mechanisms included in the apparatus of the invention are advantageously mounted on a movable platform 10 for ease of placement and removal relative to the molten metal to be sampled, which is here shown, FIG. 1, as a plurality of pools A of molten copper cast in customary manner in respective anode molds of a circumferential series of same carried by a conventional anode casting wheel W utilized in the production of cast copper anodes for an electrolytic copper refining.

A support in the form of a post 11, having an upwardly projecting rotatable shaft 11a, is mounted on the platform 10, and a sampling arm 12 is pivotally attached to the top of the post on a vertical axis of rotation, provided by shaft 11a, so as to extend laterally of the post and to pivot in an arc thereof around. In this illustrated embodiment, arm 12 is balanced on a horizontal axis of rotation provided by a pivot pin 13 that is carried by a stationary bracket structure 14 cantilevered from a mounting platform 11b rigidly secured to the projecting upper end of shaft 11a. Balancing is achieved by means of a ballast or counterweight 15, which is enclosed in a cage 16 to protect it from interference during the swinging of arm 12. Cage 16 is securely mounted on platform 11b.

The means for holding individual sampling tubes is located at the free end of the arm 12 and, as shown, takes the form of a tube clamp 17 having a stationary jaw 17a and a movable jaw 17b pivoted at 17c. The clamp 17 is held in closed, clamping position by a spring 18, see especially FIG. 5. A wire 19 connects movable jaw 17b above its pivot point to a solenoid 19a which is activated to pull the wire and thereby open the clamp 17 for either releasing a filled tube or receiving an empty tube.

Drive mechanism is attached to the post 11 for swinging the arm 12 from a work station WS on the platform 10 to a predetermined position over the molten metal to be sampled and back to the work station after the sample has been taken. The drive mechanism preferably includes a motor 20 and a combination clutch and brake assembly 21 that is connected to the motor 20 through a gearbox 22. As shown in FIG. 4, a chain 23 connects drive sprocket 24 of clutch and brake assembly 21 to a sprocket 11c rigidly secured to shaft 11a of post 11, which swings arm 12.

Operation of drive mechanism is controlled by three limit switches 25, 26, and 27 located about the stationary portion of post 11. Two of the switches, 25 and 26, define the arc traversed by the free end of arm 12 from the work station WS to the predetermined position over the molten metal to be sampled. The third switch, 27, is a momentary switch which activates clamp/solenoid 19a during the return swing of arm 12 to open tube clamp 17 and release the filled sample tube at

tube-collecting station, preferably a funnel 28 emptying into a catch receptacle 28a, here shown as located at work station WS. The three switches 25, 26, and 27 are activated by trigger members 29, 29a, and 29b, FIG. 4, which are attached to and for circumferential adjustment about shaft 11a of post 11. In operation, as shaft 11a rotates to swing arm 12 over the molten metal and then back to the work station, trigger members 29 and 29a contact first one and then the other of switches 25 and 26 respectively to limit the arcuate swing. During the return swing of arm 12, trigger member 29b actuates knee-action switch 27 to release the held sample tube into funnel 28.

In addition to swinging laterally about post 11, arm 12 in this illustrated embodiment swings vertically about the horizontal axis provided by pivot pin 13. When arm 12 is in position to take a sample from the molten metal, as shown in FIG. 2, it is swung downwardly to lower its free end—equipped with tube clamp 17—and to dip the empty sampling tube held thereby into the molten metal. This is accomplished by activating dipping mechanism mounted on a lateral extension 14a of bracket 14. The dipping mechanism comprises a lever arm 30 connected by a link 31 to sampling arm 12. Lever 30 is connected to drive mechanism 32, which may be an electric motor controlled by limit switches 33 and 34 adjustably mounted in an arcuate slot 35 so the length of vertical swing or dip of arm 12 can be varied to suit different levels of molten metal positioning.

Although in this illustrated embodiment the arm 12 is swung down to dip the sampling tube into one of the molten metal pools A, the arrangement can be such that tube clamp 17 is lowered independently of the arm 12 for the purpose.

Vertically adjustable support in the form of a post 36 is mounted on platform 10 at the work station WS and serves to support means for replacing empty sampling tubes in the tube clamp 17. Such tube-replacing means includes, in this embodiment, a tube injector mechanism 37, a container 38 for holding a plurality of empty sampling tubes 39, and a mechanism 40 for feeding individual tubes from container 38 into the injector mechanism 37, all as shown in detail in FIGS. 6, 7, and 8.

The several components of the tube-replacing means are advantageously mounted on a horizontal supporting surface 41a provided by a platform 41 and disposed below the level of tube clamp 17 when such tube clamp is positioned at work station WS. The platform 41 can have side panels 41b extending upwardly and a top (not shown), if desired, to protect the components from dust and heat. If side panels 41b are included, an opening 41c in the side panel over which tube clamp 17 passes in its swing from the work station WS must be provided to permit the empty tube held by the tube held by the tube clamp to pass therethrough.

The container 39 for holding a plurality of sampling tubes has an elongate channel 42 for holding a plurality of empty, upright sampling tubes 39, preferably evacuated glass sampling tubes, in linear alignment with tube injector mechanism 37 disposed at one end of channel 42 under the supporting surface 41a.

In the illustrated embodiment, the mechanism 40 for feeding empty tubes 39 into the tube injector mechanism 37 has a semicircular flange 43 adapted to fit around one side of a sampling tube 39. The flange is disposed within channel 42 behind the last tube 39a in the channel and urges the tubes 39 forward within channel 42 individually into an injection zone 44 disposed at the end of the channel directly above injector mechanism 37 and below tube clamp 17. Means attached to flange 43 for urging the tubes forward includes herein a conveyor carriage 45 fixably attached to flange 43 and adapted to move along a rod 45a disposed adjacent to, and extending along the longitudinal side of channel 42. Conveyor 45 is secured to a reciprocable chain 46 which is connected at one end thereof to a sprocket 47 and at the other end to a drive sprocket 48. Drive sprocket 48 is, in turn, connected with a reversible electric motor 49 mounted on the supporting surface 41a. As flange 43 urges the foremost tube 39b into injec-

tion zone 44, the tube 39b contacts a limit switch 50 located at the extreme end of the injection zone, which shuts off the power to conveyor 45 and stops the forward movement of the tubes. When the last tube in channel 42 has been injected into tube clamp 17, a trigger member 45b attached to conveyor 45 strikes a limit switch 45c at the entrance to injection zone 44. The closing of limit switch 45c reverses motor 49 and moves conveyor 45 to the opposite end of channel 42 to permit the channel to be replenished with empty tubes.

10 The injector mechanism 37 for moving tube 39b from tube injection zone 44 upwardly into tube-holding clamp 17 above includes in this embodiment a rod 51 which extends from the underside of the supporting surface 41a through an aperture 52 therein and contacts the bottom of tube 39b. Rod 51 is connected at its lower end to a cam follower 53, which is in turn connected to a rotating cam 54 driven by an electric motor 55, all attached to the underside of platform 41 by means of a pair of downwardly extending support rods 56. As rod 51 rises and inserts tube 39b into the open tube clamp 17, rotating cam 54 is in the upper portion of its arc and closes therewith a limit switch 57 attached to a securing plate 56a which is mounted on rods 56 and is adapted to be vertically adjustable on the rods. The closing of limit switch 57 closes tube clamp 17, thereby securing sampling tube 39b therein. As cam 54 continues to rotate, it closes a momentary switch 58 attached to support rods 56, activating an arm pusher mechanism 59 attached to supporting surface 41a adjacent to arm 12 and adapted to move the arm laterally away from its rest position over injector mechanism 38. The closing of momentary switch 58 also breaks the current to an electro magnet 60 releasing arm 12 from contact with electro magnet 60 which is adapted to hold arm 12 in position over tube injector 37 during the injection of an empty tube into tube clamp 17. Cam 54 continues to rotate and rod 51 drops until the cam closes a lower limit switch 61 mounted on a securing plate 56b, which stops cam 54 with rod 51 at its lowest position below injection zone 44.

40 In operation, work station WS mounted on movable platform 10 is positioned a safe distance away from the molten metal to be sampled, but within the arcuate swing of arm 12. Tube clamp 17 receives an empty sampling tube from injector mechanism 37 as described above, and arm 12 swings outwardly from the work station WS over the metal to be sampled. As the sampling tube held by tube clamp 17 reaches its proper position over the molten metal, the dipping mechanism is activated to lower the end of arm 12, enabling the lower end of the sampling tube to penetrate the surface of the molten metal. The evacuated glass tube is pierced by the hot metal, and the metal is drawn up into the tube where it solidifies. The dipping mechanism then raises the tube out of the molten metal, and arm 12 begins its swing back to its initial position at the work station. Before arm 12 reaches the work station, tube clamp 17 preferably releases the filled sample tube into funnel 28 disposed near the work station. Funnel 28 preferably is connected to a container of cold water 28a into which the filled tube drops. The cold water shatters the glass, leaving the metal plug for analysis. Tube clamp 17 then continues on to the work station, where it is available for the injection of another empty sampling tube and the initiation of another sampling cycle.

55 The apparatus can be operated manually or can be connected to a power source, such as electricity or compressed air; and can be programmed to operate automatically with timed sequencing of the desired steps in the cycle. FIG. 9 illustrates a circuit diagram for electrical programming of the apparatus for automatic sampling operation.

60 The automatic operation of the sampling arm is begun by connecting the circuit 62, 62a, 62b to an outside source of energy, preferably a 110 volt line, and closing the power switch 63 permitting the current to flow through a fuse 64 and to activate a pilot light 65. A pushbutton 66 is depressed to permit current to flow through line 67 to energize the relay coil R-1. Energizing coil R-1 sends current through lines 68,

69 to close R-1 contact 70 and R-1 contact 71, which starts the Timer No. 1. Timer No. 1 times out to close Timer No. 1 contact 72, permitting current to flow through line 73 to energize the coil 74 of the drive motor 75 for the outward swing of the sampling arm from the work station. Meanwhile, the clutch 75a has been engaged by the flow of current through line 76 from the direct current power supply 77, which was energized through line 78 and the Timed Delay Relay No. 1 switch 79 when the circuit was energized by closing power switch 63.

When the sampling arm has reached the end of its outward swing over the molten metal to be sampled, the arm closes a limit switch 80, which opens R-5 contact 81 and R-6 contact 82 through lines 83, 84, respectively, and energizes relay coil R-2 and relay coil R-3, while opening R-3 contact 79a, to deenergize coil R-1. The energizing of coil R-3 disengages the clutch 75a by opening R-2 contact 85, and engages the brake 86 by closing R-2 contact 87. At the end of the outward swing, the dip motor 88 is activated to lower the arm, and the internal switch 89 is closed through line 90 and R-3 contact 91, which was closed by the energizing of coil R-3. As the sampling arm reaches the predetermined lower position for sampling the molten metal, it closes an external limit switch 92 sending current through line 93 to activate Timer No. 2. Timer No. 2 determines the length of time that the arm remains down in the sampling position. When Timer No. 2 times out, it closes R-4 contact 97, and energizes relay coil R-4 and relay coil R-5 by closing Timer No. 2 contact 94 through the closed limit switch 95. At the same time, coil R-3 is deenergized by opening R-6 contact 82 and closing R-5 contact 96. The dip motor drives the arm upwardly through the closed contact 98 until the internal switch 89 of the dip motor 88 has been broken by the opening of external switch 92, thereby stopping the updrive of the motor.

With the opening of the external limit switch 92 the circuit is completed through line 99 to relay coil R-6 preparatory to returning the arm in a reverse swing to its initial position at the work station. R-6 contact 100 is closed to start the drive motor 75 through its reverse coil 101. At the same time, coil R-2 opens R-6 contact 81 which disengages the brake 86, and contact 87 closes to reengage the clutch 75a.

As the arm swings back toward the work station, it strikes a momentary switch 102 which energizes coil R-8 and coil R-9. Relay coil R-8 is held in a closed position through relay coil R-9, the tube limit switch 103, and the closing of R-8 contact 104. At the same time, R-8 contact 105 closes to energize the tube clamp solenoid 106 and the tube guide coil 107, which opens the tube clamp and releases the filled sampling tube into a receptacle. In addition thereto, the R-8 contact 105 energizes an electromagnet 107a which holds the arm in stationary position when the arm strikes the limit switch 95. When the limit switch 95 is contacted by the sampling arm it reverts to the open position and closes R-9 contact 108 through line 109 to energize coil R-7 and coil R-10. At the same time coil R-4 and coil R-5 are deenergized. The energizing of coil R-7 opens contact 110 of coil R-7 to disengage the clutch 75a, and closes contact 111 of coil R-7 to engage the brake 86, thereby stopping the arm.

As coil R-10 is energized, R-10 contact 112 opens and the tube injector motor 113 begins to operate to raise the injector rod with an empty sampling tube. The bottom limit switch 114 on the tube injector closes to hold in coil R-7 and coil R-10. At the same time contact 115 of coil R-10 closes, thereby starting Timed Delay Relay No. 1, and contact 116 of coil R-10 closes to energize the three-quarter travel limit switch 117 through line 118 and the normally closed timer switch 79 of Timed Delay Relay No. 1.

The tube injector rod strikes and opens the top limit switch 103 to deenergize coil R-8 and coil R-9, thereby clamping the sampling tube in the tube holder and deenergizing the electromagnet 107a. R-9 contact 108 opens to break the current from the limit switch 95 to coil R-7 and coil R-10. The tube injector strikes and closes the three-quarter limit switch 117

75 and the timer switch 79 of Timed Delay Relay No. 1. The current to the direct current power supply 77 through line 78 is momentarily broken, which releases the brake 86 and simultaneously engages the solenoid 119 for the arm pusher to push the arm away from the electromagnet 107a. The three-quarter limit switch 117 opens when the timer switch 79 of the Timed Delay Relay No. 1 reaches the open position, which drops the current from one side of the winding of the tube injector motor 113 through R-10 contact 115. Tube injector motor 113 then drives the injector rod to the bottom limit switch 114, thereby breaking the contact and applying current to the winding of the tube injector motor 113 through R-10 contact 112 to stop the motor. The unit is now in a standby position ready for the next signal, by manual or remote control, to repeat the cycle.

The mechanism for feeding individual tubes from the container to the injector mechanism requires periodic reloading to replenish the supply of sampling tubes in the lateral channel 20 of the tube container. The automated embodiment provides for retraction of the tube conveyor in the channel when the last tube has been injected into the tube clamp at the end of the sampling arm.

As the last tube is injected into the tube clamp, a 25 microswitch 120 located in the tube injection zone opens because no tube is in the injection zone. The opening of the microswitch 120 starts a Timed Delay Relay 121. When the Timed Delay Relay 121 times out, it breaks the contact 122 energizes the forward motor winding 123 to drive the tube 30 conveyor forward. The tube conveyor strikes and closes a microswitch 124 located at the entrance of the tube injection zone, which energizes relay coil R-11. At this point the green pilot light 129, which is on during normal operation, is extinguished and the red pilot light 130 is illuminated. The energizing of coil R-11 closes R-11 contact 125 and starts the current in the reverse winding of the motor 126 by breaking R-11 contact 127, which also drops the current on the forward motor winding 123. The motor drives in reverse until the tube 35 conveyor strikes and closes a third microswitch 128 located at the opposite end of the lateral channel. The closing of the microswitch 128 energizes the forward winding of the motor 121 and stops the reverse drive of the tube conveyor. The channel can now be loaded with sampling tubes.

The tube feeding mechanism remains in standby position 45 until a pushbutton 131 is depressed to activate the mechanism. Depressing the pushbutton 131 deenergizes coil R-11 by closing R-11 contact 127 and opening R-11 contact 132. The reverse winding 126 of the motor is thereby dropped out and the energized forward winding 123 drives the conveyor forward until the forward tube strikes and closes the microswitch 120 in the tube injection zone. The closing of the microswitch 120 energizes the reverse winding 126, thereby stopping the forward drive of the motor and tube conveyor. With a tube in the injection zone, the conveyor is on standby 50 until the tube injector rod lifts the tube into the tube clamp. At this point, the microswitch 120 opens and starts the Timed Delay Relay 121. As the Timed Delay Relay 121 times out, it opens the contact 122 and causes the reverse motor winding 126 to be dropped. The energized forward winding 123 drives the conveyor forward until another tube is pushed into the tube injection zone, thereby closing the microswitch 120 and stopping the forward movement of the conveyor until the tube 55 in the injection zone has been injected into the tube clamp at the beginning of the next cycle.

I claim:

1. Apparatus for taking samples of molten metal, comprising
a support adapted for positioning between the molten metal
to be sampled and a work station at a safe distance
therefrom;
an elongate arm extending from and secured to said support
for pivotal movement therewith about a vertical axis, so said
arm can be swung back and forth between the work station
and said molten metal;

sampling tube-holding means carried by the extended end of said arm;
 means for swinging said arm about said vertical axis;
 means for lowering and raising said tube-holding means with respect to the molten metal to be sampled; and
 means for releasing filled sampling tubes from said tube-holding means.

2. Apparatus as set forth in claim 1, wherein the means for lowering and raising the tube-holding means comprises a pivotal mounting for the arm on the support for pivotal movement thereat about a horizontal axis, and means for swinging said arm about the horizontal axis.

3. Apparatus as set forth in claim 1, wherein the support comprises an upright post.

4. Apparatus as set forth in claim 1, including means at the work station for successively feeding empty, individual, sampling tubes into the tube-holding means.

5. Apparatus as described in claim 4, wherein the tube-feeding means comprises in combination, a tube-injector mechanism for injecting tubes into the tube-holding means, a container for holding a plurality of empty sampling tubes, and a mechanism for feeding individual tubes from the container to the tube injector mechanism.

6. Apparatus as set forth in claim 4, wherein the support comprises an upright post.

7. Apparatus as set forth in claim 1, including a receptacle

for receiving filled sampling tubes released from the tube holding means.

8. Apparatus as set forth in claim 7, wherein the receptacle comprises a funnel leading to a container for water.

9. Apparatus for inserting empty sampling tubes into the tube-holding means of an apparatus for taking samples of molten metal, comprising in combination:

injecting means for inserting a sampling tube upwardly into the tube-holding means, said injecting means comprising a cam-actuated rod extending upwardly and adapted to be alternately raised and lowered to insert the sampling tube;

a container connected with the injecting means for holding a plurality of upright sampling tubes in adjacent horizontal relationship to each other; and
 feeding means within the container for urging the plurality of tubes horizontally along said container and for feeding each tube individually to the injecting means; said feeding means adapted to be reversed automatically to accommodate additional tubes in the container when the last tube in the container is fed into the injecting means.

10. Apparatus as set forth in claim 9, wherein the cam-actuated rod is vertically adjustable to accommodate tubes of varying lengths.
